HOLDER AND INSULATOR FOR ELECTRIC
FENCE WIRE

Dean F. Hunter, Ogden, Iowa

Application May 15, 1944, Serial No. 535,667

1 Claim. (Cl. 174—156)

My invention relates to improvements in combined holders and insulators for attaching electric fence wire to a fence post, the primary object in view being to provide a simply constructed, inexpensive device of the character indicated which is adapted for easy and quick insertion of fence wire therein and for confining such wire so that the wire cannot work or slip out of the holder.

Another object is to provide a combined holder and insulator for such wire which may be quickly attached to a fence post and locked in holding position by such attachment, and is inexpensive to manufacture and replace.

Other and subordinate objects are also comprehended by my invention, all of which, together with the precise nature of my improvements, will be readily understood when the succeeding description and claim are read with reference to the drawing accompanying and forming part of this specification.

In said drawing:

Figure 1 is a view in side elevation of my improved holder and insulator attached to a fence post,

Figure 2 is a view in vertical section taken on the line 2—2 of Figure 1.

Referring to the drawing by numerals, my improved holder and insulator, in the preferred embodiment illustrated, comprises a frame 1 including a pair of flat bars 2, 3, of any suitable metal, pivoted together at one end, as at 4, and having the opposite free ends thereof apertured, as at 5, said bars being oppositely bowed, relatively, so that the same may be swung toward each other, until the apertures 5 register, to close the frame and impart thereto an oval form, or swung from each other to open said frame. The pair of bars 2, 3 carry thereon a pair of glass, or porcelain, blocks 6, 7 of less width than the length of said bars and through which the bars extend, as shown in dotted lines in Figure 1, with said blocks centered thereon between the ends of the bars and suitably secured thereto.

The blocks 6, 7 are provided with a pair of opposed wire-confining grooves 8, 9 which extend across opposed faces of said blocks in the transverse center of the blocks and are of semi-elliptical form transversely. The grooves 8, 9 are adapted to mate when the frame 1 is closed to form a transversely elliptical wire-confining channel completely closed at its sides. Each block 6 or 7, as the case may be, is provided at one side of the groove with a lip 10 extending toward the other block and adapted to seat in a

complemental recess 11 in the other block when the frame 1 is closed. The lips 10 and complementary recesses 11 are staggered to dispose the same upon opposite sides of the median plane of the blocks 6, 7. The blocks 6, 7 are provided with tapered top and bottom portions 12, 13 so that said blocks may easily shed moisture.

The manner in which the described holder and insulator is applied and used will be readily understood. The frame 1 is opened, in the manner already described, to separate the blocks 6, 7 so that a wire W may be inserted between said blocks to be enveloped by the grooves 8, 9 when said frame is closed. When the frame 1 is closed, it is attached to a fence post 14 by nailing through the registering apertures 5 of the bars 2, 3, as shown at 15. As will be seen, by virtue of the specified arrangement of lips 10 and recesses 11, the wire confined between the grooves 8, 9 cannot slip or work out from between the blocks 6, 7.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claim.

What I claim is:

1. A holder and insulator for attaching fence wire to a post comprising a frame including a pair of bars pivoted together at one end for swinging toward and from each other to open and close the frame, respectively, said bars being oppositely bowed relatively whereby said frame when closed is of oval form, said bars having free ends provided with apertures therein adapted to register when the frame is closed and for the passage of a spike therethrough for securing the frame to a fence post, and a pair of blocks of insulation material through which said bars extend whereby said blocks are mounted on said bars, respectively, said blocks being provided with a pair of opposed transverse grooves therein mating when the frame is closed and forming when mated a wire-confining channel closed at the sides thereof, said blocks being provided with extension lips at opposite sides of the grooves, and with recesses for seating said lips when the frame is closed, said lips and grooves being staggered upon opposite sides of the median plane of said blocks to provide for the lips overlapping side by side to prevent a fence wire from escaping out of said grooves.

DEAN F. HUNTER.
